ATTORNEYS.

UNITED STATES PATENT OFFICE.

JOHN D. MINES, OF MOFFETT'S CREEK, VIRGINIA, ASSIGNOR TO HIMSELF
AND W. L. TETER, OF SAME PLACE.

IMPROVEMENT IN MILLSTONE-DRESS.

Specification forming part of Letters Patent No. 154,268, dated August 18, 1874; application filed
April 10, 1874.

To all whom it may concern:

Be it known that I, JOHN D. MINES, of Moffett's Creek, in the county of Augusta and State of Virginia, have invented a new and Improved Mill-Burr Dress; and I do hereby declare that the following is a full, clear, and exact description of the same, reference being had to the accompanying drawing forming a part of this specification, in which—

Figure 1 is a sectional elevation, and Fig. 2 a top or plan view of the bottom stone.

The invention relates to means whereby a mill-burr may be dressed so as to prepare the grain for flouring at the eye of the stone, and thus save a large percentage of the power ordinarily required under like circumstances, as well as permit the mill to be operated by twenty-five per cent. less water. These means will first be fully described in connection with all that is necessary to a full understanding thereof, and then pointed out in the claim.

A A represent the two burrs or stones of a grain-mill, the same having a face-dress of shallow, corresponding, non-radial furrows,

widening at the ends or otherwise. B is my center-dress, which is an annular concavity about eight or ten ~~inches~~ deep around the eye of the burrs, the excision from the stones being so made as to form a square shoulder, b, of the same depth. This serves to crush the grain, and not grind it into dust or powder before it comes between the grinding-faces, the bran being thus left large and flat.

The resistance to the power employed is found, by practical experiment and observation, to be greatly diminished, so that the mill may thus be run with much less power or water than usual.

Having thus described my invention, what I claim as new is—

Burrs or stones for grinding grain, provided with faces having a center-dress consisting of an annular depression, B, with shoulder b, as and for the purpose described.

JOHN D. MINES.
